UNITED STATES PATENT OFFICE.

JAMES MILLAR NEIL, OF NEW YORK, N. Y.

APPARATUS FOR ATOMIZING METALS.

1,049,314.

Specification of Letters Patent. Patented Dec. 31, 1912.

Application filed April 10, 1912. Serial No. 689,791.

To all whom it may concern:

Be it known that I, JAMES MILLAR NEIL, of New York, in the county of New York and State of New York, have invented certain new and useful Improvements in Apparatus for Atomizing Metals; and I hereby declare that the following is a full, clear, and exact description thereof, reference being had to the accompanying drawings, which form part of this specification.

This invention relates to the art of atomizing metal, and is an improvement upon the apparatus shown in my application for patent filed December 12, 1911, Serial No. 665,229.

The particular object of the present invention is to produce an apparatus which will be especially adapted for successfully atomizing zinc; while also capable of use for atomizing other metals; and its subsidiary object is to simplify the construction of my prior apparatus while enhancing its efficiency.

By this apparatus I am enabled to obtain metals in an extremely fine state of subdivision, but unoxidized, and in such physical condition that even on exposure to ordinary atmospheric conditions they remain unoxidized; and metals in this condition I term "atomized". Such atomized metals are especially adapted for use in recovering precious metals from cyanid solutions obtained during the treatment of ores by cyanid.

I will explain my present invention with reference to the accompanying drawings in which—

Figure 1 is a vertical sectional elevation of the apparatus, the atomizer head being in elevation. Fig. 2 is a transverse section of the apparatus on line 2—2, Fig. 1. Fig. 3 is an enlarged side view of the atomizing head. Fig. 4 is a similar but reverse side view of the atomizer head. Fig. 5 is a longitudinal sectional view of such head; and Fig. 6 is a longitudinal sectional view on line 6—6, Fig. 3.

As shown in the drawings the apparatus comprises a furnace 2, which may be formed of a metal cylinder lined with refractory material 2^a; and divided into upper and lower compartments by a transverse partition 2^e; this furnace may be heated in any suitable or desired manner. As shown I have provided a hydrocarbon burner 3 at-

tached to the side of the furnace and adapted to supply hot gases to the upper compartment, the blast of burning gases entering the furnace through an opening 2^b in the side thereof. The lower compartment can be heated by means of a burner 3^x similar to burner 3, the blast from said burner entering the lower compartment 2^f through an opening 2^h in the wall of the furnace.

A crucible 1 is placed in the upper compartment and may be supported upon the partition 2^e. Connected with the crucible and depending into the compartment 2^f is a J-shaped tube 4 which may be of highly refractory metal, or other suitable material, and is shown as provided with a flange 4^a on its upper end by which it is practically suspended from the bottom of the crucible, and is positioned therein by means of a refractory filling 1^b so that the top of the tube 4 is practically flush with the bottom of the crucible and the molten metal in the crucible will be directed into the duct in said tube. The lower upwardly curved end of the tube 4 may be closed by a head or plug 4^b tapped thereto and having a flat top provided with a small aperture 4^c through which the molten metal can exude. This atomizing head 4^b lies adjacent to or within an opening 2ⁱ in the wall of the furnace in chamber 2^f.

Secured to or formed on the upturned end of the tube 4, adjacent head 4^b, and at the side next the burner 3^x, is a flange 4^e which rises above the head 4^b and extends horizontally at an angle to the tube, as shown in Fig. 2. Attached to and supported by this flange 4^e, adjacent head 4^b, is a jet-head 5 which is provided with a shank 5^a engaging a horizontal slot in the flange 4^e and secured by a nut 5^b, see Fig. 4. This jet-head is connected to an atomizing fluid supply, such as superheated steam from a boiler, not shown; but any other suitable fluid may be used. The pipe 5^e enters chamber 2^f through an opening 2^m in the side thereof. The jet aperture 5^c in the head 5 is adjusted so that the jet or blast of atomizing fluid issuing therefrom will impinge upon the metal exuding upwardly through the aperture 4^c, as shown in Figs. 4 and 5.

I have found it quite important because of the differences in the size of the crucible and tube and the amounts of metal therein, and especially when treating metals such as

zinc which are liable to chill very quickly, to place the crucible in one compartment and the tube and atomizer in another compartment and to heat them by independent means, so that the temperature of both can be regulated to a nicety and the metal can be kept in the proper molten condition in the crucible without overheating, and can also be kept in the necessary fluid condition in the tube 4 without endangering the latter by overheating.

The zinc or other metal to be atomized is placed in the crucible 1, which is heated by the blast from burner 3; and the tube 4 and atomizing head are heated by the blast from burner 3^a. In this way the metal in the crucible can be quickly reduced, and the tube and atomizer head kept at the proper temperature to prevent chilling of the metal which descends to the atomizer from the crucible.

Operation: The molten metal from the crucible descends through the tube 4 and exudes upwardly through the aperture 4^c onto the top of the atomizer head 4^b; and the exuding molten metal is flattened out upon the surface of the head in a thin sheet or film and then immediately thrown off the head and dissipated in atomized condition by the jet of heated fluid forcibly issuing from the aperture 5^c in the head 5. The metal is thus instantaneously reduced to a fine, almost impalpable, powder. Suitable means should be provided for catching and collecting such atomized metal. The atomizing agent issuing from the jet 5^c should have a temperature equal to, and preferably higher than, the melting point of the metal being treated; and when the apparatus is thus operated the metal is atomized and solidifies before oxidation can occur. In this way the metals can be atomized or finely subdivided without the necessity of surrounding the atomizer with de-oxygenated gases.

What I claim is:

1. In apparatus for atomizing metals, a crucible; means for heating the crucible; a conduit depending from the crucible, and having at its lower end an upwardly directed fluid outlet; means for heating the conduit; and means for directing a jet of atomizing fluid against the metal exuding upwardly from said outlet.

2. In atomizing apparatus, the combination of a furnace; a crucible; and means for heating the crucible; a conduit depending from the crucible having an upturned lower end and an upwardly directed fluid outlet; means for heating the conduit; and means for directing a jet of atomizing fluid against the metal issuing from the tube.

3. In an atomizer, the combination of a furnace having upper and lower compartments; a crucible in the upper compartment, and means for heating the crucible; a conduit extending from the crucible into the lower compartment, and having an upwardly directed fluid outlet at its lower end; means for heating the conduit; and means for directing a jet of atomizing fluid against the metal exuding upwardly from the outlet.

4. In an atomizer, the combination of a furnace having upper and lower compartments; a crucible in the upper compartment; and means for heating the crucible; a conduit or tube extending from the crucible into the lower compartment, and having an upwardly directed fluid outlet at its lower end; means for heating the conduit; and means for directing a jet of atomizing fluid against the metal exuding upwardly from the outlet.

5. In an apparatus for atomizing metals, the combination of a furnace having upper and lower compartments, a crucible in the upper compartment; a conduit or tube extending from the crucible into the lower compartment, and having an upturned lower end to upwardly direct fluid to the outlet at the lower end of said conduit; means for independently heating the conduit; and means for directing a jet of atomizing fluid against the metal issuing from the tube.

6. In an apparatus for atomizing metals, the combination of a furnace having upper and lower compartments, a crucible in the upper compartment; a conduit extending from the crucible into the lower compartment and having an upwardly directed fluid outlet at its lower end; means for directing a jet of atomizing fluid against the metal exuding upwardly from the outlet, and means for independently heating the said compartments.

7. In atomizing apparatus, the combination of a furnace having upper and lower compartments; a crucible in the upper compartment; a conduit extending from the crucible into the lower compartment and having an upturned lower end and an upwardly directed fluid outlet in the end of said conduit; means for directing a jet of atomizing fluid against the metal issuing from the outlet; and means for independently heating the crucible and the conduit.

8. In apparatus for atomizing metals, the combination of a furnace having upper and lower compartments, a crucible in the upper compartment; a conduit or tube extending from the crucible into the lower compartment, and having an upwardly directed fluid outlet at its lower end; and means for directing a jet of atomizing fluid against the metal exuding upwardly from the outlet; with means for heating the crucible in the upper compartment, and independent means for heating the conduit and atomizer head in the lower compartment.

9. In atomizing apparatus, the combination of a furnace having upper and lower compartments; a crucible in the upper compartment; a conduit extending from the crucible into the lower compartment and having an upturned lower end and an upwardly directed fluid outlet in the end of said conduit, and means for directing a jet of atomizing fluid against the metal issuing from the tube; with means for heating the

- crucible in the upper compartment and independent means for heating the conduit and atomizer head in the lower compartment.
- 5 9. Apparatus for atomizing metals, comprising a furnace; a crucible; a J-shaped tube connected with the bottom of said crucible; an aperture for the escape of metal at the lower end of said tube; and means adjacent this aperture to direct a jet or atomizing fluid against the metal exuding through said aperture.
- 10 10. Apparatus for atomizing metals, comprising a furnace; a crucible; a J-shaped tube connecting with the bottom of said crucible; an atomizer head on the lower end of said tube provided with an upwardly directed aperture for the escape of metal; and means adjacent the head to direct a jet of atomizing fluid against the metal exuding through said aperture.
- 15 11. Apparatus for atomizing metals, comprising a furnace having upper and lower compartments, a crucible in the upper compartment, a J-shaped tube connecting with the bottom of said crucible extending into the lower compartment, and having an aperture for the escape of metal at its lower end; a jet-head adjacent this aperture adapted to
- 20 direct a jet of atomizing fluid against the metal exuding through said aperture; and means for conducting highly heated atomizing fluid to said jet head.
- 25 12. Apparatus for atomizing metals, comprising a furnace; a crucible; a J-shaped tube connecting with the bottom of said crucible having an upwardly directed aperture for the escape of metal at its lower end; and means adjacent this aperture to direct a jet
- 30 of atomizing fluid against the metal exuding through said aperture; with means for heating the crucible in the upper compartment, and independent means for heating the atomizing devices in the lower compartment of the furnace.
- 35 13. Apparatus for atomizing metals, comprising a furnace having upper and lower compartments, a crucible in the upper compartment; a tube connected with the bottom
- 40 of said crucible and extending into the lower compartment, having an upwardly directed aperture for the escape of metal at its lower end; a jet-head adjacent this aperture to direct a jet of atomizing fluid against the
- 45 metal exuding through said aperture, and means for conducting highly heated atomizing fluid to said jet head; with means for heating the crucible in the upper compartment, and independent means for heating
- 50 the tube and atomizing devices in the lower compartment of the furnace.
- 55 14. Apparatus for atomizing metals; comprising a furnace having upper and lower compartments; a crucible in the upper compartment, and means for heating said compartment; a tube connected to the bottom of the crucible and extending into the lower compartment, and having its lower end upturned; a plug connected to the end of said tube having an upwardly directed opening for the escape of the heated metal; a jet-head adjacent the said aperture to direct an atomizing jet against the metal exuding through said aperture, and means for conducting highly heated atomizing fluid to said head.
- 60 15. Apparatus for atomizing metals; comprising a furnace having upper and lower compartments; a crucible in the upper compartment; a tube connected to the bottom of the crucible and extending into the lower compartment, and having its lower end upturned; a head connected to the end of said tube having an outlet for the escape of the heated metal; a jet-head adjacent the said outlet adapted to direct an atomizing jet against the metal exuding therethrough, and means for conducting highly heated atomizing fluid to said head; with means for heating the crucible in the upper compartment, and independent means for heating the tube and atomizing devices in the lower compartment.
- 65 16. Apparatus for atomizing metals; comprising a furnace having upper and lower compartments, a crucible in the upper compartment, a J-shaped tube connected to the bottom of the crucible and extending into the lower compartment, and having its lower end upturned; a plug connected to the end of said tube having an upwardly directed aperture for the escape of the heated metal; and a jet-head adjustably mounted upon said tube and adapted to direct an atomizing jet against the metal exuding through said aperture; with means for conducting highly heated atomizing fluid to said head; means for heating the crucible in the upper compartment, and independent means for heating the tube and atomizing devices in the lower compartment.

In testimony that I claim the foregoing as my own, I affix my signature in presence of two witnesses.
